UNITED STATES PATENT OFFICE.

JAMES A. MURDEN, OF NEWPORT NEWS, VIRGINIA.

PLOW.

1,117,079.

Specification of Letters Patent.

Patented Nov. 10, 1914.

Application filed April 14, 1914. Serial No. 831,855.

To all whom it may concern:

Be it known that I, JAMES A. MURDEN, a citizen of the United States, residing at Newport News, in the county of Warwick 5 and State of Virginia, have invented new and useful Improvements in Plows, of which the following is a specification.

This invention relates to plows, and it has particular reference to an improved riding attachment to be used in connection 10 with walking plows of ordinary construction.

The invention has for its object to produce a simple and efficient riding attachment which may be readily applied to an ordinary walking plow without interfering with the operation thereof, the plow being free to be guided in the usual manner.

A further object of the invention is to 20 produce a simple and efficient riding attachment in connection with a floor upon which the operator may stand if so desired.

With these and other ends in view which will readily appear as the nature of the 25 invention is better understood, the same consists in the improved construction and novel arrangement and combination of parts which will be hereinafter fully described and particularly pointed out in the claims.

30 In the accompanying drawing has been illustrated a simple and preferred form of the invention, it being, however, understood that no limitation is necessarily made to the precise structural details therein exhibited, 35 but that changes, alterations and modifications within the scope of the claims may be made.

In the drawing,—Figure 1 is a perspective view of a plow equipped with the improved riding attachment. Fig. 2 is a side elevation of the same partly in section and showing the floor raised to an out-of-the-way position. Fig. 3 is a top plan view of the riding attachment removed from the 45 plow. Fig. 4 is a sectional detail view taken on the line 4—4 in Fig. 3. Fig. 5 is a detail view similar to the left hand end of Fig. 2, but showing the floor in position for operation.

50 Corresponding parts in the several figures are denoted by like characters of reference.

A designates the beam; B—B, the handles; C, the standard, and D, the mold board 55 of an ordinary walking plow.

The riding attachment comprises two side members 15, each of which has an intermediate curved or offset portion 16 producing divergent rear ends 17 which are supported on an axle 18 having ground 60 wheels 19. The side members 15 are also connected together by a cross bar or brace 20. Pivottally supported on one of the side members near the rear end thereof is a bracket 21 supporting a seat 22 which may 65 be moved to various positions relatively to the side members of the frame. When the operator desires to ride he may move the seat to a position intermediate the side members, but if he desires to stand, the seat may 70 be swung to a rearward position in alignment with the side member with which the bar 21 is pivotally connected.

The side members 15 are provided with 75 grooves or recesses 23 in the inner side faces thereof, said grooves having downward offsets 24 at their front ends and upward offsets 25 at the rear ends thereof. These grooves or recesses receive the ends of a cross bar 26 having arms or brackets 27 that support a floor or platform 28. When the cross bar 26 is moved rearwardly in the recesses 23 and into engagement with the offsets 25, the brackets 27 will be supported on the cross bar 20 from which they extend downwardly, thus supporting the floor or platform in convenient position for the operator to stand on. Should it be desired to dispense with the use of the platform, the brackets 27 may be swung upwardly, permitting the cross bar 26 to be moved forwardly in the recesses 23 until it drops into the offsets 24, and the platform may now 80 be connected with a hook 29 at the end of a flexible element 30 which may be attached 85 to the plow beam or to one of the rounds that connect the handles in any convenient manner.

One of the side members of the riding attachment may be provided with a socket 31 90 in which the stick or handle of a sunshade or umbrella may be mounted.

It will be seen from the foregoing description that I have provided a simple and inexpensive riding device which may be conveniently attached to the beam A of a riding plow by means of a bolt 33, whereby a flexible connection is established between the plow and the riding attachment, enabling the ground wheels to adapt themselves freely 105 110 115

to the contour of the land. The riding attachment may be detached from the plow by simply removing the bolt 33.

When the plow is equipped with the improved attachment, the operator may ride on the seat 22 or stand on the platform 28, or the latter may be swung to an out-of-the-way position, thus enabling the operator to walk behind the plow and guide the same in the customary manner, when preferred, without necessity of dismantling the riding attachment.

Having thus described the invention, what is claimed as new, is:—

- 15 1. The combination with a plow, of a riding attachment comprising side members, a wheel carrying axle supporting the same, and a cross bar connecting the side members, said side members being provided with grooves in their opposed faces, a cross bar slidable in said grooves, brackets extending from the slidable cross bar and adapted to rest on the cross bar supported on the side members, and a platform carried by the brackets.
- 20 2. In a riding attachment for plows, side members provided in their opposed faces with grooves having downward offsets at

their front ends and upward offsets at their rear ends, a cross bar slidable in the grooves, 30 platform carrying brackets associated with said cross bar, and a member extending between the cross bar to support the platform carrying brackets when the cross bar associated therewith is in engagement with the 35 upward offsets at the rear ends of the recesses.

3. A riding attachment for plows comprising side members provided in their opposed faces with recesses having downward offsets 40 at their front ends and upward offsets at their rear ends, a cross bar slidably engaging the recesses, platform carrying brackets associated with the cross bars, a cross bar connecting the side members and adapted to 45 support the platform carrying brackets, and means for supporting the platform in a raised position when the slidable cross bar engages the downward offsets at the front ends of the recesses in the side members. 50

In testimony whereof I affix my signature in presence of two witnesses.

JAMES A. MURDEN.
